(57) CLAIM

The ornamental design for a display screen or portion thereof with animated graphical user interface for displaying fund information, as shown and described.

DESCRIPTION

FIG. 1 is a front view of a first image in a sequence of a display screen or portion thereof with animated graphical user interface for displaying fund information, showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof; and,

FIG. 8 is a front view of an eighth image thereof.

The long-short dashed lines indicate the display screen or portion thereof and form no part of the claimed design. The short-short dashed lines and broken text represent portions of an animated graphical user interface for displaying fund information that form no part of the claimed design.

The appearance of the animated image sequentially transitions between images shown in FIGS. 1-8. The process or period in which one image transitions to another image forms no part of the claimed design.
